SLACK ADJUSTER

Carl E. Tack, Chicago, Ill., assignor to American Steel Foundries, Chicago, Ill., a corporation of New Jersey

Application June 3, 1952, Serial No. 291,498

3 Claims. (Cl. 74—522)

This invention relates to slack adjusters and more particularly to a novel slack adjuster normally utilized to compensate for wear in brake rigging of railway car trucks.

As well known to those familiar with the brake rigging art, a brake lever is generally adapted to carry a brake shoe which, in turn, is operative to engage the wheel tread of a related wheel and axle assembly. In a well known type of brake rigging for railway car trucks, a brake lever-brake shoe assembly is disposed on each side of an associated wheel, and connecting means, such as a single strap paralleling the wheel or multiple straps straddling the wheel, offer support for the lower end of the related brake levers. An example of this type of brake rigging is the patent to Simanek No. 1,969,159, issued August 7, 1934. In such a construction a slack adjuster consists of means for reducing the effective length of said straps in order to accommodate wheel and shoe wear.

It is a general object of the invention to devise a novel slack adjuster constructed and arranged to prevent dirt, moisture and other foreign matter from fouling threaded members therein.

A more specific object of the invention is to devise a novel slack adjuster wherein telescoping members are in sealed engagement and form a completely enclosed cylinder within which is disposed screw thread means.

Another specific object of the invention is to devise a novel spring lock in combination with the above described slack adjuster, thereby preventing accidental adjustment of said device.

The foregoing and other objects and advantages of the invention will become apparent from a consideration of the specification and accompanying drawings, wherein:

Figure 1 is a top plan view of an embodiment of the invention;

Figure 2 is a side elevational sectional view of the invention taken substantially along lines 2—2 of Figure 1, and

Figure 3 is an end elevational view of the embodiment as seen in Figure 2.

Describing the invention in detail, a housing, generally designated 2, desirably a casting, is formed having a base portion 4 and a cylindrical portion 6 integrally formed with and disposed above said base portion 4. The cylindrical portion 6 extends longitudinally of the housing and is interrupted intermediate its ends by the slot 8, separating the cylindrical portion 6, at a point centrally of and directly above the base portion 4, into segments 5 and 7. The cylindrical portion 6 is formed and arranged to define a passageway 10, preferably of circular form in cross section, disposed to communicate with the slot 8 on opposed sides thereof. It is to be noted that the passageway 10 is open at one end as at 12, and at its other end is substantially closed by the wall 14 formed integrally with the cylinder 6. A hole or aperture 16 is formed centrally of the end wall and may be aligned with the longitudinal axis of the passageway 10.

2

A hollow cylindrical bushing 18 is preferably telescoped within the passageway 10 in such a manner as to circumferentially abut the inner surface of the passageway and extend through the separating slot 8, thereby interconnecting the segments 5 and 7 of the passageway 10. The bushing 18 is tightly fitted within the passageway 10, that is, a metal-to-metal fit, thereby assuring a sealed connection therebetween. The bushing 18 may be fixedly secured in its assembled position in any convenient manner, such as by welding to the cylinder 6 as at 20.

In a preferred embodiment of the invention, a forked brake lever is employed and is partially shown at 22 in Figure 3. At the lower extremities of the forked lever 22, coaxial holes 24 with bushing inserts 26 are provided.

15 A separate yoke 28 of U-shaped form is disposed within the slot 8 adjacent to and separate from brake lever 22 with its open end directed downwardly embracing a portion of the bushing 18. At the lower end of the extremities of the yoke, pin and hole connection as at 30 is made to the base portion 4 of the housing 2. Thus the yoke is securely attached to the housing 2. On opposite sides of the yoke 28, and preferably in a horizontal plane passing through the longitudinal axis of the passageway 10, circular outwardly directed bosses 32 are presented. 25 Each boss 32 is pivotally received by the bushed hole 24 of the related fork of the brake lever 22. Thus, pivotal connection is provided between the housing 2 and brake lever portion 22 of the brake rigging.

The adjusting screw 36 comprises a male threaded cylindrical body portion 38 and a lug 40 positioned on one end of the body portion in alignment with the longitudinal axis of said body portion. The aperture 16 of the end wall 14 offers complementary reception for the lug 40 of the screw 36, said lug extending through said aperture and rigidly connected to the end wall by any suitable means such as welding at 41. Thus the screw is rigidly positioned within the passageway 10 of the housing 2, said passageway and screw having a common longitudinal axis.

40 A body or sleeve 42, of hollow cylindrical form in cross section, having an opening 43 at one end and an integrally formed wall 44 at the other end is preferably telescoped within the bushing 18 and disposed to surround the screw 36. As noted, the sleeve 42 presents the cylindrical recess 46, the diameter of which is greater than the diameter of the screw thus providing radial clearance for the screw during the relative movement therebetween hereinafter described. Adjacent the open end 43 of the body 42, the recess 46 is reduced in diameter and presents the female screw threads formed to complement and engage the mentioned male threads on the screw 36. This construction provides for relative controlled movement between the screw 36 of the housing 2 and the body 42, upon relative rotation of said body.

45 It is to be noted that the sleeve or body 42 circumferentially abuts the inside surface of the bushing 18, that is, the sleeve is snugly fitted within the bushing. The clearance between the interfitting bushing 18 and the sleeve 42 approaches a substantially metal-to-metal fit, hence accommodating relative rotation between the parts, but being operative to substantially seal the passageway 10, thus preventing dirt, moisture or other foreign matter from entering therein and clogging the screw threads.

50 55 This feature is particularly desirable in railway operation where the brake rigging is carried externally on the trucks and near the ground.

60 It should be noted that the connection between the screw 36 and the housing 2 is external of the housing. Thus, in the event that the screw threads become fouled, thereby freezing the sleeve within the housing, the exter-

nal connection can be broken and the adjuster dismantled and repaired without breaking the housing 2.

The wall 44 of the body 42 presents the solid cylindrical boss 50 which, in the preferred embodiment, is loosely received by the hole 52 of the partially shown brake strap 54. Centrally of the boss 50 and integral therewith, a lug 56, preferably of square cross section is formed to extend outboardly of the strap 54 and to be received by a complementary hole of an associated adjusting nut 58. Aligned apertures 60 and 62 are presented by the lug 56 and nut 58, respectively, and provide for pin connection of the nut to the lug.

The adjusting nut 58 of the preferred embodiment consists of two portions, one of which is the adjusting portion 64 characterized by its hexagon cross section which is adapted to mate with a wrench or other conventional tool for rotation of said nut. A locking portion 66 is arranged on the opposite end of said nut and is characterized in the preferred embodiment by its octagon cross section disposed intermediate spaced parallel retaining flanges 67 and 69 peripherally disposed on said nut. It is to be noted that any polygon formation of the adjusting portion or locking portion of the nut 58 would satisfy the requirements of the invention.

Spring lock means 70 are provided to prevent accidental rotation of the nut which would result in a variation of the slack position. As best seen in Figure 3, the vertically aligned holes 72 and 74 are provided in the related strap 54 on each side of the nut 58. It is to be noted that the distance A from the center of the holes 72 and 74 to the vertical axis passing through the center of the adjusting nuts as seen in Figure 3, is equal to or less than the perpendicular distance B from the center of the nut 58 to a given flat on the octagon locking portion 66. The spring lock means 70 consists of a U-shaped wire spring having the leg portions 76 and 78 disposed within the holes 72 and 74, respectively, of the strap 54. The connecting portion 80 of the spring lock 70 is positioned intermediate the spaced retaining flanges 67 and 69 and abutting the octagon portion of the nut 58. Due to the relation between the mentioned distances A and B, the connecting portion 80 is distorted from its normal shape and resiliently abuts a related flat of said octagon portion. The pressure exerted by said spring lock 70 maintains the nut in a given position, thus preventing the mentioned accidental rotation. However, the flexibility of the spring lock 70 accommodates rotation of the nut when a sufficient twisting moment is applied thereto, as would be the case during manual adjustment of the slack device. The strap 54 may be maintained in level position by a guide or support bar (not shown) which is in turn secured to a pair of ears 9 formed on the cylindrical portion 6 of the base 4.

In operation, rotation of the nut 58 concurrently rotates the body or sleeve 42, which in turn, varies the relative position of said body on the screw 36. This action varies the relative position between the brake lever 22 and the strap 54, hence accommodating wear on the braking surfaces.

The invention has been illustrated as applied to a brake lever-single strapped brake rigging assembly, but, as would be obvious to those skilled in the art, only slight modification would be required to apply the invention to a multiple strap brake assembly or to other portions of the brake rigging, such as, for example, pull rods and it is to be understood that the invention as claimed comprehends such applications.

I claim:

1. In a slack adjuster arrangement, a base having spaced coaxial bores and an end wall closing the outer end of one of said bores, a cylindrical bushing extending between and secured within said bores, a yoke having

spaced arms straddling the medial portion of said bushing, said arms being secured at their ends to said base, coaxial trunnions projecting from opposite sides of said yoke, a brake lever having a bifurcated end straddling said yoke and provided with bearing apertures to receive said trunnions, a screw coaxially positioned within said bushing and having one end thereof fixed to said end wall, an internally threaded adjustment sleeve having its inner end threaded onto said screw and snugly slidably engaged within said bushing, the outer end of said sleeve being closed by an end wall having a cylindrical boss projecting outwardly therefrom coaxial with the sleeve, a lug on the outer end of said boss, a nut secured to said lug, and a brake strap having a bearing portion journaled on said boss and engaged between the sleeve end wall and said nut.

2. In a slack adjuster arrangement, a base having spaced coaxial bores and an end wall closing the outer end of one of said bores, a cylindrical bushing extending between and secured within said bores, a yoke having spaced arms straddling the medial portion of said bushing and secured at their ends to said base, coaxial trunnions projecting from opposite sides of said yoke, a brake lever having a bifurcated end straddling said yoke and provided with bearing apertures to receive said trunnions, a screw coaxially positioned within said bushing and having one end thereof fixed to said end wall, an internally threaded adjustment sleeve having its inner end threaded onto said screw and snugly slidably engaged within said bushing, the outer end of said sleeve being closed by an end wall having a cylindrical boss projecting outwardly therefrom coaxial with the sleeve, a lug on the outer end of said boss, a nut secured to said lug, and a brake strap having a bearing portion journaled on said boss and engaged between the sleeve end wall and said nut.

3. In a slack adjuster for a related railway brake mechanism, a housing having a slot extending transversely thereof, a passageway defined within said housing and having portions communicating with said slot on both sides thereof, a cylindrical bushing sleeved within said passageway extending between said portions and fixedly secured to said housing, a wall on said housing at one end of said passageway closing same, a screw abutting said wall and nonrotatably connected thereto and axially aligned with said cylindrical bushing, a yoke disposed within said slot and having arms embracing said bushing and extending therebelow to fixedly engage said housing, spaced coaxial trunnions on said yoke to be journaled on a brake lever, a sleeve having an open end receiving said screw and in threaded engagement therewith, said sleeve having a closed end to seal the end of said passageway, said closed end having a journal portion coaxial with said sleeve to engage a brake strap, and means on the closed end of said sleeve to adjust the position of said sleeve relatively to said housing.
